MOBILE HOIST

William H. Lannert, Skokie, Ill., assignor to
 Chicago Pump Company, a corporation of Illinois

Application May 14, 1942, Serial No. 442,925

11 Claims. (Cl. 212—8)

This invention relates to a hoist and particularly to a mobile hoist for operating on various pieces of apparatus. While the hoist hereinafter described and claimed is of general application, it is particularly designed for use where stationary anchor means are provided to which the hoist body may be rigidly attached. In particular the hoist disclosed herein is especially adapted for operation on sewage treating tank aeration apparatus such as is described and claimed in my copending application Serial No. 429,230, filed February 2, 1942. The hoist will be described in connection with such sewage apparatus merely by way of example.

Sewage treating systems generally include a multiplicity of tanks into which are suspended aeration apparatus for supplying predetermined quantities of air to the sewage contents of the tanks. As particularly described in the hereinbefore mentioned application, the apparatus for feeding air is swingably disposed from stationary parts disposed at the tank side. It is necessary to have access to these swingable units and for this purpose catwalks are generally provided along the tank sides and leading to the various pieces of sewage apparatus. Service men and service apparatus may move along these catwalks to the various pieces of sewage treating equipment.

Heretofore it has been the practice to have fixed portions of the hoisting mechanism incorporated into each sewage treating station. This practice is uneconomical and involves an unnecessary duplication of such mechanism. The hoist of my invention is designed to dispense with this practice because it may be wheeled on the catwalks to any desired station and there be rigidly anchored to a stationary portion of the pivotally suspended aeration apparatus to swing it from the sewage tank to a position within easy reach from the catwalk.

In general the hoist comprises a more or less elongated frame upon which the entire hoisting apparatus is carried. This frame is preferably mounted upon casters or rollers for ready movement. While the dimensions of the frame are of no intrinsic importance, the frame as designed for use in a sewage plant is preferably long in comparison to its transverse dimension so that it may be readily maneuvered within narrow spaces. One end of the frame, which may for convenience be termed the rear end, is provided with an adjustable clamping means for anchoring the hoist to a fixed portion of the work to be operated upon, in this particular case a portion of the

sewage treating system. The adjustable clamping means in its simplest form is a sort of vise which is adapted to engage the work to be operated upon.

5 It is preferred to have the clamping means engage predetermined fixed regions of the stationary portion of the apparatus and to this end such apparatus is provided at these regions with suitably prepared contoured parts which may be readily and firmly engaged. Pivotally carried by the frame is at least one beam or arm in which the actual hoisting function is localized. As shown, the hoist has a plurality of beams pivotally mounted to move in vertical planes.

15 Preferably, the beams have coincident pivotal axes and such pivotal axes are, preferably, although not necessarily, coincident with the axis along which clamping pressure is applied. The beams are actuated by suitable means such as a flexible cable attached to one beam and passing over a portion of the other beams.

20 In conjunction with the beams and as part of the hoisting mechanism the truck carries a suitable motor driven winch to operate upon the cable, and suitable motor control equipment for either manual or automatic control.

25 In the normal use of the hoist herein described, the truck is wheeled to a particular desired station. The truck body is positioned and the beams 30 are swung out with the cable being paid out accordingly. Preferably, at least one of the beams is provided with an engaging means which in this particular instance engages a portion of the sewage aerator. This engagement is automatic 35 and is accomplished by the positioning of the truck during the clamping operation. Thereafter the hoist may be operated in the normal fashion to either swing out an aerator unit from the tank or if the aerator unit has been out to 40 return the same.

The invention will now be described in detail with reference to the drawings wherein:

45 Figure 1 is an isometric side elevation of the hoist in clamped position and operating on an aerator unit;

Fig. 2 is a top plan view looking down upon the hoist with the hoist free of the aerator unit and the beams resting on the truck;

Fig. 3 is a sectional detail along 3—3 of Fig. 2 and showing the details of the clamp adjustment; and

Fig. 4 is a sectional detail along 4—4 of Fig. 2 and showing the details of the stationary portion of the clamping means.

55 Referring now to the drawings, the hoist com-

prises a truck frame 10 of pressed steel or the like having a generally rectangular outline. As is clearly evident from Fig. 2, the frame is long in comparison to its width. For mobility, the frame is provided with a centrally disposed caster 11 mounted upon a fork 12 pivotally carried by frame 10 near one end thereof. Fork 12 has attached thereto a handle 13 which may be used for moving the truck and working the same into position. This end of the truck may be conveniently referred to as the front.

Carried at the rear end of frame 10 and forming a part thereof is a U-shaped clamping portion. This clamping portion comprises a transverse section 15 and sides 16 and 17. It should be noted, particularly from Fig. 2, that transverse section 15 extends beyond the side of frame 10. This increased width at the clamping region endows the hoist with transverse stability. Sides 16 and 17 carry supporting wheels 18 and 19 suitably mounted on axles so that the entire hoist has a three wheel suspension.

As is evident from Fig. 1, the U-shaped clamping portion is so mounted with respect to truck frame 10 as to have an upward tilt whereby sides 16 and 17 extend upwardly at an angle from the horizontal base line of the truck. This is to provide desirable clearance above ground. The free ends 20 and 21 of sides 16 and 17 have bearings upon which are pivotally mounted beams 23 and 24. These beams incline toward each other so that at free ends 25 and 26 the distance between the beams is substantially less than at the pivot points. The free ends 25 and 26 are rigidly retained in position by a cross block 27. As shown here, beam 23 extends substantially perpendicular from the pivot axis while beam 24 is inclined. However, both beams may be inclined or the relationship may be reversed if desired. Both beams function as a unit as far as hoisting is concerned. By virtue of the straddling effect, stability of the hoist is assured.

As shown clearly in Fig. 4, the anchored portion of beams 24 is rotatably carried by clamping side 17 of the frame on a suitably machined bearing surface 28 of a centering block 28 carried by side 17. Beam 24, having a suitably machined aperture at the anchor end, may rotate on bearing surface 28 and is retained in position by a face plate 29. Face plate 29 and block 28 are, preferably, contoured to provide a hollow region 29' into which a predetermined part of the stationary apparatus may fit for clamping purposes. This contouring may be a simple circular cavity. A convex contour may be provided if desired. Face plate 29 and region 29' function as the anvil for a clamp.

Beam 23 has its pivot portion 30 disposed in such a manner that it may rotate around a sleeve 31. This sleeve is supported at the free end of clamp side 16 by means of bolts 32 engaging an outwardly extending flange 33 forming a part of the sleeve structure. It will be noted that sleeve 31 extends transversely of side 16 on opposite sides of supporting flange 33.

A clamping pin or bolt 35 is slidably disposed within sleeve 31 and is adapted to extend beyond the two ends of the sleeve. Bolt 35 has one portion 36 terminating in a blunt tapered clamping tip 37 extending transversely of clamp side 16 and pointing toward region 29' on the opposite clamp side 17. The bolt axis may be considered as the axis of the clamping means. An auxiliary beam 38 is carried by portion 36 and extends perpendicularly therefrom for a dis-

tance. The length of auxiliary beam 38 is preferably of the same order as that of beam 23. Auxiliary beam 38 is carried by portion 36 in any suitable manner. Thus, it is shown as rigid therewith but may be rotatable thereon if desired.

Bolt 35 also has a threaded portion 40 extending outwardly from the frame. Surrounding threaded portion 40 of the bolt is the flanged end 41 of sleeve 31. The free end of flange 41 is provided with an annular recess 42 and is adapted to have a cover plate 43 retained by bolts 44 engaging flange 41. Cover plate 43 has its inner surface substantially in line with the inside surface of sleeve 31 so that recess 42 is closed to form an annular groove.

A sleeve 47 having a shouldered end 48 is adapted to be locked in groove 42 and retained in aligned position with respect to sleeve 31. For this purpose shouldered end 48 of sleeve 47 has a groove 49 into which cover plate 43 may be disposed. It is clear that cover plate 43 must be split or divided into two parts to be seated in groove 49. At this end of sleeve 47, a nut portion 50 is provided having a thread cooperating with the threaded portion 40 of bolt 35. The main body of sleeve 47 is provided with an enlarged bore 51 substantially larger than the diameter of threaded portion 40 of bolt 35. Hence bolt 35 may move freely. The end of threaded portion 40 of bolt 35 is reduced to provide a small threaded portion 52 upon which is disposed a lock nut 53. The diameter of lock nut 53 is such that it will slide smoothly within bore 51 but will be stopped by the threaded portion 50 of sleeve 47. This provides a limit to inward travel of bolt 35. Shouldered end 48 of sleeve 47 has a flange 54 to which is bolted a hand wheel 55.

By virtue of the construction hereinbefore described, it is clear that rotation of hand wheel 55 will cause sleeve 47 to rotate. Since axial movement of sleeve 47 is prevented, it follows that clamping bolt 35 will be moved lengthwise depending upon the direction of rotation of hand wheel 55. It is understood that the bolt portion 36 of bolt 35 is of a size to fit smoothly within sleeve 31.

Referring now to auxiliary beam 38, a heavy supporting saddle construction 65 is shown as carried by beam 38. This saddle may be formed of any suitable metal such as pressed steel and consists of two arms 66 and 67 connected by a generally semicircular portion 68. Arms 66 and 67 extend toward the opposite side of the frame and, as shown here, are particularly adapted to engage the body portion 18 of the swinging part of a sewage aerator construction as more specifically described and claimed in the copending application referred to above.

The free end of auxiliary beam 38 has attached thereto a cable 71 that normally passes through a guide block 72 carried by block 27. Cable 71 then continues on to a suitable winch 73 driven by a motor 74. A storage compartment 75 for slack cable 71 may be provided. A suitable motor control 76 having either automatic, manual or combined control characteristics may be provided so that overrunning may be avoided.

In order to provide a compact construction, the beams and truck construction are so correlated as to permit of the beams being folded down in nested relationship over the truck. Thus, the entire hoist occupies a minimum of space and provides a compact construction.

In order to operate the hoist it is necessary to

position the saddle 65 below body portion 70 of the swinging part of a sewage aerator. This may be done by maneuvering the hoist into clamping position. In this position of the truck and prior to the actual clamping to the aerator, the beams are swung up from the truck with beam 38 advanced sufficiently so that saddle 65 is transversely in line to engage portion 70 of the aerator. This will naturally depend upon the initial position of the aerator. Thus, if the aerator is in a raised position and is to be lowered then beam 38 will not have to be turned very far. On the other hand, if the aerator is in an operative position within the tank, that is if the aerator is depending downwardly, then beam 38 will have to be turned over even beyond the position shown in Fig. 1.

Cable 71 will, naturally, be paid out to permit all the beams to swing. When beam 38 is adjusted properly so that saddle 65 engages the aerator then the clamp may be tightened to anchor the hoist rigidly in position. The movement of beam 38 with bolt 35 results in saddle 65 being positioned under part 70 of the aerator. Thereafter the hoist and aerator may be considered as one and the hoist operated in the usual fashion.

As clearly shown in Fig. 1, beam 38 is the one that is actually used for hoisting and is normally in advance of beams 23 and 24 which operate as a unit. By virtue of this angular advance and the fact that cable 71 passes over guide block 72, a hoisting component on beam 38 will always be provided within a wide range of beam positions. Thus if beam 38 were dropped so that it extended outwardly from the truck then a direct pull on cable 71 would not result in any substantial hoisting effort on the cable extended along the beam. By having the auxiliary beams 23 and 24 stand up from the truck a true hoisting construction results.

In practice when hoisting, the angle between beam 38 and beams 23 and 24 remains substantially constant until beams 23 and 24 are in position where cable 71 goes straight through block 72. Then beam 38 is the only one to be moved. An automatic winch control may be provided for stopping hoisting action when beam 38 has reached a predetermined position.

During the reverse operation, in case it is desired to lower an aerator, it is not necessary to raise beams 23 and 24. The turning of beam 38 away from the truck may be utilized to pull up beams 23 and 24. In order to provide this action, cable 71 is provided with a lug 77 for engaging or locking in guide member 72 and thus providing a positive pull on beams 23 and 24. If desired, fixed stops may be provided for limiting the outward movement of beam 38 and also the movement of auxiliary beams 23 and 24.

By providing the maximum truck width at the clamping axis it is evident that a substantial base for the hoist exists and thus stability is insured. Inasmuch as sides 16 and 17 must be sufficiently strong to withstand the clamping force advantage may be taken of this by locating the pivotal axis of the beams on these sides. In particular, by having the pivotal and clamping axis coincident, maximum hoisting stability is assured while most efficient use of the strength of materials is obtained.

Finally, it should be noted that the clamping end of the entire truck is the lighter end. Since this end may have to be raised under some conditions to engage for clamping, the reduced ef-

fort for doing this is desirable. As made however, the truck may be run directly into position with little or no lifting. A lug 78 may be provided on the front end of the frame 10 to anchor this end in place during hoisting operation.

It should also be noted that during pivotal movement of beam 38 a movement of pivot bolt 35 takes place. However, since the movement will always be a fraction of the pitch distance 10 between threads on part 40 it need not affect the clamping action. By having sufficient play in the cooperating clamping surfaces, a satisfactory pivotal clamp action may still be obtained irrespective of the position of beam 38.

15. What is claimed is:

1. A hoist comprising a truck frame movably mounted, said truck frame having one end thereof as the hoisting end, clamping means carried by the hoisting end of said truck for rigidly fastening said truck in operative relation to the work to be operated upon by said hoist and yet allowing for relative rotatable movement between the work and the clamping means, said clamping means having an axis about which said work is rotated, at least one beam, means on said beam for engaging a part of the work to be hoisted, and means for moving said beam and cause the work to rotate about said clamp axis and thereby hoist the work, said means forming a substantial portion of the entire weight of the hoist and being concentrated at the end remote from the hoisting end.

2. A hoist comprising a movable truck having a hoisting end, clamping means on said end for rigidly engaging a stationary part of work to be operated upon and yet allowing for relative rotatable movement between the work and the clamping means, said clamping means having an axis, at least one beam pivotally mounted and having a center of movement substantially concentric with said clamping means, means on said beam for engaging a part of the work to be hoisted, and means for moving said beam and cause the work to rotate about said clamp axis and thereby hoist the work.

3. A hoisting device comprising a movable truck having a hoisting end, adjustable clamping means for engaging a stationary portion of the work to be operated upon and yet allowing for relative rotatable movement between the work and the clamping means, said clamping means having an axis about which said work is rotated, a pair of independently swingable beams, means on one of said beams for engaging a part 55 of the work to be hoisted, a cable attached to the end of said one beam and passing through a support on said other beam, and means for moving said cable to move said beams and cause the work to rotate about said clamp axis and thereby hoist the work.

4. A hoisting device comprising a movable truck having a hoisting end, manually adjustable clamping means for engaging a stationary portion of the work to be operated upon, a pair of independently swingable beams, means on one of said beams for engaging the work to be hoisted, a cable attached to the end of said one beam and passing through a support on said other beam, means for moving said cable to move said beams 70 for hoisting purposes, said last named means forming a substantial portion of the entire weight of the hoist and being concentrated at the end remote from the hoisting end.

5. A hoist comprising a movable substantially narrow elongated truck body, said body having

a hoisting end having a width substantially greater than the truck body proper, adjustable clamping means on said hoisting end for rigidly engaging a stationary portion of work to be operated upon, a pair of beams pivotally mounted and having a concentric pivot axis substantially coaxial with said clamping means, a cable connecting said two beams, means on one of said beams for engaging the work to be operated upon, and means for moving said cable for hoisting.

6. A hoist comprising a movable, substantially narrow elongated truck body, said body having a hoisting end with a width substantially greater than that of the truck body proper, adjustable clamping means on said hoisting end for rigidly engaging a stationary portion of work to be operated upon, a pair of beams pivotally mounted and having a concentric pivot axis substantially coaxial with said clamping means, said adjustable clamping means including a pivot bolt around which said beams move, said pivot bolt having a threaded portion, a rotatable threaded member cooperating with the threaded portion of said pivot bolt, means for preventing movement of said rotatable member along the axis of said bolt, means for mounting said pivot bolt so that said pivot bolt moves longitudinally in response to turning of said rotatable member, a clamping anvil carried by said hoisting end spaced from said pivot bolt but in line with the axis thereof whereby said pivot bolt may be moved lengthwise to clamp a part between it and the anvil, a cable tied to one of said beams and passing over the other beam and means for moving said cable for hoisting.

7. A movable hoist comprising a substantially narrow elongated body, said body having a hoisting end with a width substantially greater than that of the truck body proper, said hoisting end having a pair of spaced arms for embracing a stationary portion of the work to be operated upon, one of said arms having a journal, a pivot bolt movably mounted in said journal for both longitudinal and rotational movement, said pivot bolt having a threaded portion, a manual control including a nut portion cooperating with the threaded bolt portion, means for mounting said manual control on said one arm whereby said manual control may only be rotated to force said

5 pivot bolt to move lengthwise thereof, at least one beam pivotally mounted to move around an axis parallel with that of the pivot bolt and means for swinging said beam for hoisting purposes.

8. The structure of claim 7 wherein said beam axis is coincident with the pivot bolt axis.

9. The structure of claim 7, wherein an additional beam is provided, both beams having coincident axes around which they move, and a cable tied to one beam for hoisting purposes and sliding over the other beam end, and means for moving said cable for hoisting.

10. A hoist comprising a truck frame movably mounted, said truck frame having one end thereof as the hoisting end, adjustable clamping means carried by the hoisting end of said truck for rigidly fastening said truck in operative relation to the work to be operated upon by said hoist, said clamping means including an elongated bolt 20 adapted to move back and forth for clamping or releasing purposes, a beam rigidly carried by said bolt and extending perpendicularly therefrom, a work engaging member carried by said beam and adapted to rest under a part to be raised, and means for moving said beam to raise or lower said work engaging part as desired, said work engaging part being adapted to be moved into position under the part to be raised during the clamping of the hoist.

11. A hoist comprising a truck frame movably mounted, said truck frame having one end thereof as the hoisting end, said hoisting end having a width substantially greater than that of the truck body proper, said hoisting end having two spaced clamping portions, means for rigidly clamping a stationary member between said clamping portions for rigidly anchoring said hoist, a beam extending from each side of said truck at the hoisting end pivotally mounted thereon, means for rigidly joining the free ends of said beams to form a composite beam pivotally moving as a unit, a second beam carried by said clamping end and pivotally mounted, a cable attached to said second beam and passing over said first composite beam and means for imparting hoisting effort to said cable.

WILLIAM H. LANNERT.
